(57) CLAIM

The ornamental design for a laptop lapdesk, as shown and described.

DESCRIPTION

FIG. 1 is a perspective view of a laptop lapdesk showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The subject matter in broken lines is disclaimed and forms no part of the claimed design.
